PROCESS FOR PRODUCING LAURIC-ACETIC-GLYCERIDE

Leo Phillip Hubbuch, Wilmington, Del., and Raymond E. Thomas, Newburgh, N. Y., assignors to E. I. du Pont de Nemours & Company, Wilmington, Del., a corporation of Delaware

No Drawing. Application April 24, 1934,
Serial No. 722,128

1 Claim. (Cl. 260—106)

This invention relates to improvements in the manufacture of mixed esters of polyhydric alcohols, and more particularly to a new method for preparing mixed glycerides especially suitable as softeners for nitro-cellulose compositions which are to be used in the manufacture of artificial leather.

To those skilled in the art it is known that a suitable softener for artificial leathers has two functions, (1) to soften the coating without making it sticky or oily, and (2) to keep the coating soft and pliable over a long period of time. We have discovered that to accomplish the first result, the softener must have the proper degree of solvent action for the film-forming ingredient of the coating composition, and to obtain the second result, the softener must be substantially non-volatile and not susceptible to oxidation under the usual conditions for use of artificial leathers. Castor oil, the chief softener now in use, meets the first requirement but is not outstanding. It is notoriously deficient in regard to the second requirement because it oxidizes readily and causes embrittlement of the coating. Long chain saturated or non-oxidizable glycerides such as coconut oil are sufficiently non-volatile in character for use as softeners but have low solvent power and consequently render the surface of the coating oily or greasy. Short chain saturated glycerides such as triacetin are not only too volatile, but are also water sensitive and have too great a solvent power, thus rendering the coating sticky. Mixtures of these exhibit the bad features of both. However, when they are chemically combined by a method which assures that neither type is present as such in substantial amounts, an extremely useful softening agent is produced, so that a pure mixed glyceride of the proper type should be the ideal softener for artificial leather coating compositions.

Various methods of making mixed glycerides have been disclosed in the prior art. Thus, Schwartz U. S. Patent No. 1,558,299 discloses the direct esterification of the polyhydric alcohol with a mixture of organic acids, with or without sulfuric acid as a catalyst, the sulfuric acid being later removed either by washing or neutralization with sodium acetate; the heating of coconut oil and glacial acetic acid, followed by esterification of the liberated coconut oil acids by

glycerol which may be partially esterified with acetic acid; heating coconut oil, glacial acetic acid, and sulfuric acid, followed by esterification of the liberated coconut oil acids and the excess acetic acid with glycerol; the heating of coconut oil and triacetin with or without sulfuric acid as a catalyst; and ester interchange by heating coconut oil, glacial acetic acid, glycerol, and sulfuric acid together. None of the above methods involve an ester interchange of the coconut oil acid radicals of coconut oil to a product wherein some of the glycerol hydroxyls are rendered free, the remainder being esterified by coconut oil acid radicals. All of the processes given above result in a product which is non-uniform, containing either free triacetin or free coconut oil in greater or less amounts, and objectionable therefore for use in artificial leathers.

This invention has as an object the provision of pure mixed polyhydric alcohol, especially glycerol, esters of long and short chain essentially saturated fatty acids, and processes for making them. A further object is the provision of cellulose derivative compositions containing these uncontaminated mixed glycerides. Other objects will appear hereinafter.

These objects are accomplished by the following invention wherein the glycerol ester of the long chain acid, e. g. trilauroin or coconut oil, is alcoholized by heating with glycerol at elevated temperature, the resulting product is esterified by means of an esterifying derivative of the short chain fatty acid, and the volatile by-products are removed by heat treatment combined with certain other auxiliary steps.

The initial glycerol ester should have an iodine number of not more than 35, i. e. the long chain acid must be essentially saturated. This is necessary because materials with higher iodine numbers will yield oxidizable softeners. The long chain fatty acid should have 10 to 18 carbon atoms and the short chain fatty acid 1 to 4 carbon atoms. The long chain fatty acid should have at least ten carbon atoms because the lower acids impart objectionable odors; it should have not more than 18 carbon atoms in order to obtain liquid products. The short chain fatty acid should have less than five carbon atoms in order to produce products which will not exude from the film.

The process of the present invention is illustrated by the following examples which illustrate more specific details of the invention, but are not to be regarded as limitative thereof.

5 *Example 1*

Constituents	Parts
10 Coconut oil.....	43.2
Glycerol.....	10.0
Acetic anhydride.....	32.6

15 The coconut oil and glycerol are placed in a kettle or flask fitted with a reflux condenser and an arrangement for stirring and blowing with carbon dioxide. These two ingredients are not miscible. The mixture is blown with CO_2 and stirred very rapidly during the heating operation which consists of bringing the charge up to 250° C. 20 in two hours' time and maintaining it at this temperature for approximately four hours or until a sample removed from the kettle and cooled shows no tendency to exude glycerol and contains no free glycerol, as shown by extraction with water. The charge is then cooled to 130° C. and the acetic anhydride added gradually over a period of 15 minutes. The mixture is then refluxed for 1 1/4 hours. The condenser is changed to a distilling position and the charge is blown with CO_2 and heated to 170° C. in about two hours and maintained at this temperature for about 3 hours longer or until no odor of acetic acid can be detected in the liquid in the kettle. The charge 25 is then cooled and the blowing with CO_2 discontinued. The product is a thin, brown oil of an acid number of approximately 2.0. The yield is 30 96.8% of the theory. (The major portion of the acetic acid liberated by the acetic anhydride can be reclaimed; in one experiment 78.5% of the acid was recovered as an 82.5% solution.) The product as judged by its acid number has very little uncombined acetic and/or coconut oil acids. Practically no water-soluble portion can be removed by extraction thus showing the substantial absence of glycerol and triacetin. The oil 35 when used in the proper proportions gives an artificial leather of excellent feel and unusual durability. The film shows no greasiness, thus indicating that substantially no coconut oil is present.

40 In case a softener with less solvent action on nitrocellulose than the above is desired, it can be made by varying the proportions of coconut oil, glycerol and acetic anhydride. The following example will serve to illustrate this:

55 *Example 2*

Constituents	Parts
60 Coconut oil.....	75.3
Glycerol.....	10.0
Acetic anhydride.....	32.3

65 The equipment and procedure are practically the same as for the preceding experiment. The oil and glycerol are heated at 250° C. for about 5 hours or until the mixture becomes homogeneous. The charge is cooled to 130° C. and the acetic anhydride added. The solution is then refluxed 70 for 2 hours. The condenser is changed to a distilling position and the charge is blown with CO_2 and heated to 170° C. in about 2 hours and maintained at this temperature for about 2 hours or until no odor of acetic acid can be detected in 75 the liquid in the kettle. The product is a light

brown thin oil of acid number around 2.0. The yield is 96.2% of the theory. (In this experiment, 80.9% of the acetic acid formed was recovered as a 94.4% solution.) The product, similar to that from Example 1, contains practically no free acetic and/or coconut oil acids and only a trace soluble in water, thus indicating the presence of only a minute amount of free triacetin and glycerol. This softener when used in the proper proportions with nitrocellulose makes an artificial leather coating ideal from the standpoints of quality and durability.

10 The product is greatly improved and the time of preparation shortened by using a slightly alkaline catalyst in the first step of the reaction. 15 The following example will illustrate this:

Example 3

Constituents	Parts
Coconut oil.....	42.7
Glycerol.....	10.0
Litharge.....	0.3
Acetic anhydride.....	33.6

20 The apparatus is the same as that used in Example 1. The coconut oil, glycerol, and litharge are blown with CO_2 , stirred rapidly and heated up to 170° C. in 1/2 hour and kept at 170° C. for 1 hour. Generally suitable conditions are 150-30 225° C. for 3 hours at the lower temperature varying to 3/4 of an hour at the higher temperature. The charge is cooled to 130° C., the acetic anhydride added and the solution refluxed for 2 hours. The acetic acid formed is finally removed 35 by vacuum distillation by heating the charge in vacuo for one hour up to 130° C. followed by 3 hours at 130° C. The charge is then given a short steaming to distill off the remaining acid and to regenerate the litharge which is easily 40 removed by filtration. The product is a light yellow, thin oil of acid number around 2.0. The product has no odor of acetic acid. No portion of it is extracted with water. The product, unlike contaminated products prepared by different methods, gives an artificial leather which is 45 highly satisfactory and durable.

Another method for preparing these mixed glycerides is based on the fact that oxalic and malonic acid esters will lose CO_2 on heating to 50 form respectively formates and acetates. The following example will illustrate the technique for the preparation of a mixed lauric-formic glyceride by this method.

55 *Example 4*

Constituents	Parts
Coconut oil.....	36.8
Glycerol.....	10.0
Oxalic acid.....	24.3

60 The apparatus is the same as that used in the other examples. The coconut oil is alcoholized with the glycerol by blowing with CO_2 , stirring rapidly and heating for about 4 hours at 250° C. The monoglyceride formed is transferred to an open kettle and cooled to 110° C. The oxalic acid is added and the blowing with CO_2 and heating continued for 8 hours, the temperature being 65 kept at 110° C. The temperature is then raised to 160°-170° C. and maintained there for 2 hours or until no further odor of formic acid can be noticed. The product after filtration is a brown, 70 thin liquid of an apparent acid number of 45.7. 75

The product prepared by this method is not nearly so satisfactory as those made by the above methods as shown by the fact that it tends to form a greasy film of lower durability when used as an artificial leather softener.

The mixed lauric-acetic glyceride type of softener can be made by using malonic acid in place of oxalic acid as the following example will illustrate:

Example 5

Constituents	Parts
Coconut oil	144.1
Glycerol	10.0
Malonic acid	36.7

The coconut oil is alcoholized with glycerol as in the previous examples by blowing with CO_2 , stirring rapidly and heating the mixture at 250°C . for 2 hours (due to the small amount of glycerol required to produce the diglyceride, the time of alcoholysis is considerably reduced). The charge is transferred to an open kettle and cooled to 140°C . The malonic acid is added and the mixture is stirred and heated gradually to 170°C . over a period of 2 hours and is held at this temperature for $1\frac{1}{2}$ hours longer. The product so obtained after the charge has been cooled is a thin, brown oil of acid number of 6.3. It can be used as a softener in artificial leather in which capacity it gives a coating of the proper limpness without undesirable stickiness or greasiness. This artificial leather does not show the outstanding durability characteristic of those containing improved softeners as prepared under Examples 1 to 3 inclusive.

The above examples are for the preparation of the softeners of the mixed lauric-acetic glyceride type for use in artificial leather, etc. The following coating compositions containing these products are illustrative of their usefulness.

Example 6

	Parts by weight
Softener of Example 1	15.1
Extracted pyro nitrocellulose	15.1
Lithopone pigment	13.6
Ethyl acetate	22.4
Ethyl alcohol	33.8

This composition, when spread on cloth and suitably dried, gives an excellent artificial leather which has a limp feel without stickiness or greasiness and which can be embossed, printed, etc. readily in accordance with well-known methods. The durability of this artificial leather is outstanding.

Example 7

	Parts by weight
Softener of Example 2	20.8
Extracted pyro nitrocellulose	11.3
Lithopone pigment	14.4
Ethyl acetate	21.4
Ethyl alcohol	32.1

The artificial leather produced from this coating composition is pliable, non-sticky, non-greasy, and after six months' exposure is still very pliable. A similar composition with castor oil as the softener becomes brittle in about three months.

In the foregoing examples glycerol, coconut oil, and acetic anhydride have represented the reac-

tants and litharge the catalyst. Other fatty glycerides such as palm kernel oil, porpoise oil, Japan wax (tripalmitin), Chinese vegetable tallow, cohune oil, myrtle wax, coconut stearin, babasu oil, etc. may be used. Different proportions of oil, glycerol, and acid anhydride may be used, depending upon the ratio of low molecular weight to high molecular weight acid radicals desired in the final softener. Alcoholysis catalysts other than litharge such as lime, barium oxide, zinc oxide, etc. may be employed in the alcoholysis step. In the alcoholysis step the glycerol may be replaced by other polyhydric alcohols such as diethylene glycol, sorbitol, pentaerythritol, monobutyltin, monobenzyltin, and the like. The relative amounts of fatty glyceride and polyhydric alcohol and the alcoholysis conditions should be so chosen that substantially all polyhydric alcohol is present as an only partially esterified compound. In the final esterification step the acetic anhydride may be replaced by other saturated aliphatic monobasic acids and acid derivatives such as propionic acid, butyryl chloride, propionic anhydride, acetyl chloride, etc. The acid anhydride is preferred because of ease and rapidity of reaction (as compared to the acid) and because no hydrohalide, which discolors the product, is formed. In view of the necessity for final removal of by-products, it is necessary that the acid or acid derivative be a volatile one. Acetic acid may be used in the esterification step, provided no more than an amount molecularly equivalent to the free hydroxyls of the alcoholized oil is used. Then in the final steaming or blowing step the by-products removed are essentially water. The saturated monobasic fatty acid should contain not more than four carbon atoms, or the esterifying fatty acid derivative should be derived from such a fatty acid.

The chief uses for products of the present invention are as softeners in cellulose derivative compositions e. g. nitrocellulose, ethyl cellulose, cellulose isobutyrate, benzyl cellulose, cellulose propionate, cellulose butyrate, etc., for the manufacture of artificial leather. They may also be employed, however, with natural resins, with synthetic resins, with bitumens, with other plasticizers, with solvents, pigments, fillers, etc. for use in molding, as adhesives or binders, and as impregnating, toughening and water-proofing agents for paper, wood, textiles, stone, etc.

The softeners of the mixed glyceride or lauric-acetic glyceride type are characterized in being adapted to be made in a great variety of compositions with a uniformity therein not hitherto obtained, a greatly improved color, and at a cost of preparation much less than the methods hitherto used.

The above description and examples are intended to be illustrative only. Any modification or variation therefrom which conforms to the spirit of the invention is intended to be included within the scope of the claim.

We claim:

A process for preparing lauric-acetic-glyceride which comprises heating approximately 43 parts of coconut oil, approximately 10 parts of glycerol, and approximately 0.3 part of litharge at $150-225^\circ \text{C}$. for $\frac{3}{4}$ to 3 hours, esterifying the intermediate glyceride with acetic anhydride, removing the acetic acid formed by distillation and steaming, and the litharge by filtration.
